Int. Cl. D17—99

U.S. Cl. D56—1

FIG. 1 is a front elevational view of a housing for an electronic musical tone synthesizer or similar article, showing my new design in closed position;

FIG. 2 is a side elevational view in closed position, the opposite side being substantially a mirror image thereof;

FIG. 3 is a top plan view in closed position;

FIG. 4 is a rear elevational view in closed position;

FIG. 5 is a front elevational view in opened position;

FIG. 6 is a side elevational view in opened position, the opposite side being substantially a mirror image thereof;

FIG. 7 is a top plan view in opened position; and

FIG. 8 is a fragmentary cross-sectional view to an enlarged scale, taken on line 8-8 in FIG. 1.

I claim:

The ornamental design for a housing for an electronic musical tone synthesizer or similar article, substantially as shown and described.
